UNITED STATES PATENT OFFICE

168,651

LAWN SPRINKLER

Michael J. Moran, Detroit, Mich.

Application July 30, 1952, Serial No. 20,824

Term of patent 14 years

(Cl. D91—1)

To all whom it may concern:

Be it known, that I, Michael J. Moran, a citizen of the United States of America, residing in Detroit, in the county of Wayne, State of Michigan, have invented a new, original, and ornamental Design for a Lawn Sprinkler, of which the following is a specification, reference being had to the accompanying drawing, forming a part thereof, wherein:

Fig. 1 is a perspective view of a lawn sprinkler showing my new design;

Fig. 2 is a plan view of the lawn sprinkler;

Fig. 3 is a side elevational view of the lawn sprinkler and

Fig. 4 is an end elevational view of the lawn sprinkler.

The dominant features of my design reside in the portion of the design illustrated in solid lines.

I claim:

The ornamental design for a lawn sprinkler, as shown and described.

MICHAEL J. MORAN.
